UNITED STATES PATENT OFFICE

107,376

DESIGN FOR A DRESS

Margaret Michelson, New York, N. Y.

Application October 25, 1937, Serial No. 72,397

Term of patent 3½ years

To all whom it may concern:

Be it known that I, Margaret Michelson, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the application of cordings on the sleeves and skirt portion in the manner and on the dress, as shown.

I claim:

The ornamental design for a dress, substantially as shown and described.

MARGARET MICHELSON.
